CLAIM

The ornamental design for a soldering station, as shown and described.

DESCRIPTION

FIG. 1 is a perspective view of a soldering station showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The uniform broken lines in the drawings depict portions of the soldering station that that form no part of the claimed design.

The dash dot broken lines define the enlargement regions and form no part of the claimed design.
